(57) **CLAIM**

The ornamental design for a bee hive pollen collector, as shown and described.

DESCRIPTION

FIG. 1 is a front, top, left side, isometric perspective view of a bee hive pollen collector in accordance with our design; FIG. 2 is a rear, bottom, right side, isometric perspective view of the bee hive pollen collector of FIG. 1;

FIG. 3 is a front elevation view of the bee hive pollen collector of FIG. 1; FIG. 4 is a rear elevation view of the bee hive pollen collector of FIG. 1;

FIG. 5 is a top plan view of the bee hive pollen collector of FIG. 1;

FIG. 6 is a bottom plan view of the bee hive pollen collector of FIG. 1;

FIG. 7 is a left side elevation view of the bee hive pollen collector of FIG. 1; and,

FIG. 8 is a right side elevation view of the bee hive pollen collector of FIG. 1.

1 Claim, 6 Drawing Sheets
